UNITED STATES PATENT OFFICE.

EDWARD LEE SOULÉ, OF SAN FRANCISCO, CALIFORNIA.

METAL-BENDING MACHINE.

1,018,086.

Specification of Letters Patent. Patented Feb. 20, 1912.

Application filed May 16, 1911. Serial No. 627,538.

To all whom it may concern:

Be it known that I, EDWARD LEE SOULÉ, a citizen of the United States of America, residing at San Francisco, in the county of 5 San Francisco and State of California, have invented certain new and useful Improvements in Metal-Bending Machines, of which the following is a specification.

This invention relates to metal-bending 10 devices and, more especially, to a device for bending metal rods, pipes and the like in one or more desired angles.

Owing to the present universal use of concrete reinforced by metal, it has become necessary that a simple, efficient and easily operated metal-bending mechanism be had to facilitate the work of such construction. With this end in view the present device, which combines simplicity, durability, compactness and cheapness of construction with 20 ease and rapidity of operation, has been invented.

The following description, read in connection with the accompanying drawings, 25 will enable persons skilled in the art to which my invention relates to understand and to practice my invention in the form in which I employ it; but it will be understood that my invention is not limited to the precise form and details of construction herein 30 illustrated and described, as the same may be changed or modified in various particulars without departing from the spirit of my invention and the scope of the claims.

Referring to said drawings:—Figure 1 is a plan view of my device, with the duplicate right-hand portion cut away, showing a metal rod bent therein. Fig. 2 is a side elevation, in broken detail, of the adjustable 40 arm. Fig. 3 is an end elevation of the bar clamping member. Fig. 4 is an end elevation of the swivel member through which the brace for the adjustable arm passes. Fig. 5 is a side elevation of the brace for 45 the adjustable arm showing a plan view of the pivoting end in broken detail.

Referring to said drawings by numerals: 50 suitably spaced guide members 1, of any preferred form but more properly of channel iron as here shown, are adapted to be mounted upon any suitable support or table and secured thereto by means of bolts 2. Said guide members are held or braced by stiffening plates 3 secured thereto in any suitable manner but preferably, as here

shown, by means of bolts or rivets. Slidably mounted upon said guide members 1 is the bar engaging member 4 formed in any suitable manner but by preference, as here shown, it consists of a section of channel-iron provided with a slot 5 for the reception of the bar to be bent. Said member 4 is mounted upon plates 6, to which it is secured in any suitable manner, for the purpose of elevating the same sufficiently to allow the bar to ride in the slot 5; and is further provided with plate 7 adapted to fit between the guide members 1 and act as a guide for said member 4 in its adjustment and also as a brace during the operation of bending. Member 4, plates 6 and plate 7 are provided with recesses in alinement for the reception of the threaded bolt 8. Bolt 8 carries clamping member 9, shown most clearly in Fig. 3, which is held in position upon said bolt by any suitable means but preferably by the wing-nut 10. As will be understood, the upwardly turned ends of clamping member 9 are adapted to engage and bear upon the inner surfaces of the 80 downwardly extending or flange portion of the guide members 1. It will be readily understood that the bar clamping member 4 may be swiveled to permit of greater range in the angle of bending and also that, instead of being slid back and forth by hand, its position may be changed by means of screw or other mechanism. The same applies to the other movable parts, but one preferred form being here shown. An adjustable arm 11, provided with a longitudinal slot 12 throughout the greater portion of its length and terminating at one end in an offset portion 13 said portion being provided with a bar receiving slot, is mounted upon 90 said guide members 1. A screw bolt 14 passes through the aforesaid slot 12 and is provided at its head with a washer 15 to engage said arm 11. A clamping member 16 carrying above it a rectangular member 17 is 95 carried by said bolt and held in position thereon by any suitable means but preferably by the wing-nut 18. Pivoted to said arm 11, near the offset end thereof, is a brace bar 19 adapted to pass through the 100 recess in an eye-bolt 20 slidably mounted between the aforesaid guide-members 1. Said eye-bolt 20 carries thereon a rectangular guide member 21 and a clamping member 22 held in position thereon by any 110

suitable means but preferably by a wing-nut 23. It will be readily understood that the action of the clamping members 16 and 22 is the same as that described for the 5 clamping member 9.

As has been said, other arrangements of my device could be made without departing from the spirit of my invention as, for instance, the adjustable arm 11 could be placed 10 beneath the bar retaining member 4 with good results, so also other means for sliding the parts to new positions could be used, likewise screw operated mechanism, lever operated cams or other means may be employed for causing the bend without departing from the spirit and scope of my invention.

To practice my invention, the parts being set for the desired bends the bar to be bent 20 is placed in the slot of member 4, a section of pipe is then slipped over the bar and brought to a point near where the bar enters the slot, force is then applied until the bar has been bent to the desired angle. When 25 a further bend is required the section of pipe is slipped back out of the way and the bar allowed to rest in the slot of the offset portion 13 of arm 11, when a further bend may be made in the same manner at this 30 point. So, by varying the positions of the different members, it will be seen that any desired angle may be formed at any point on the bar.

Having described my invention, what I 35 claim as new and desire to secure by Letters Patent, is:

1. In a metal bending machine, a suitable base, guide members mounted upon said base, a bar retaining member, supporting 40 means mounted upon said guide members beneath said retaining member and clamping mechanism carried by said retaining member for clamping the same in any position upon said guide members.

45 2. In a metal bending machine, a suitable base, guide members mounted upon said base, a bar retaining member, supporting blocks beneath said member, a guide block beneath said supports adapted to fit the slot 50 between said guide members and clamping mechanism carried by said retaining member for clamping said member in any position upon said guide member.

55 3. In a metal bending machine, a suitable base, guide members mounted upon said base, a bar retaining member mounted upon guide members and an arm adapted to receive the bent bar for further bending.

4. In a metal bending machine, a suitable 60 base, guide members mounted upon said base, a bar retaining member and an adjustable arm mounted upon said guide mem-

bers and adapted to receive the bent bar for additional bending.

5. In a metal bending machine, a suitable 65 base, guide members mounted upon said base, a bar retaining member and an adjustable arm mounted upon said guide members said arm being provided with an offset portion containing a slot for the reception of 70 the bent bar to permit of additional bending.

6. In a metal bending machine, a suitable 75 base, guide members mounted upon said base, a bar retaining member, an adjustable arm provided with a longitudinal slot and clamping means passing through said slot and engaging said guide members for the purpose of clamping said arm in any position.

7. In a metal bending machine, a suitable 80 base, guide members mounted upon said base, a bar retaining member, an adjustable arm provided with a longitudinal slot mounted upon said guide members, bracing means for said arm and clamping mechanism carried in said slot and engaging said 85 guide members.

8. In a metal bending machine, a suitable 90 base, guide members mounted upon said base, a bar retaining member, an adjustable arm mounted upon said guide members, bracing means connected to said arm and adjustable clamping mechanism adapted to receive said bracing means to clamp the same to said guide members. 95

9. In a metal bending machine, a suitable base, guide members mounted upon said base, a bar retaining member, an adjustable arm mounted upon said guide members, bracing means pivotally connected to 100 said arm and clamping mechanism adapted to receive said bracing means to clamp the same to said guide members.

10. In a metal bending machine, a suitable 105 base, guide members upon said base, a bar retaining member, an arm mounted upon said guide members and adapted to receive the bent bar for additional bending and bar bending mechanism as described.

11. In a metal bending machine, a suitable 110 base, guide members upon said base, a bar retaining member, an arm mounted upon said guide members and adapted to receive the bent bar for additional bending, bracing means connected to said arms and 115 said guide members and bar bending mechanism as described.

In testimony whereof I hereunto affix my signature in presence of two witnesses.

EDWARD LEE SOULE.
